UNITED STATES PATENT OFFICE

2,478,302

BUCKET ELEVATOR

George Ernest Moyer, Alturas, Calif.

Application February 24, 1947, Serial No. 730,249

6 Claims. (Cl. 198—140)

1.

This invention represents improvements in a bucket elevator for carrying and elevating loose material such as rock, gravel, sand, etc.; the elevator being of the type which comprises a plurality of buckets hinged together as an endless chain which is supported at its upper and lower ends by pairs of sprockets, at least one pair of which is driven.

One object of the present invention is to form the buckets and to hinge the same together in a manner which effectively prevents access of foreign substances from the buckets to the hinge assembly, and to the teeth of the sprockets which support and drive the bucket elevator. In this manner wear and damage to the above working parts is materially reduced, avoiding the necessity of frequent repair or replacement thereof.

Another object of the invention is to provide a bucket elevator, as in the preceding paragraph, in which the buckets are formed and cooperate so as to mechanically shroud and guard the peripheral portions of the sprockets which are in engagement with the buckets.

A further object of the invention is to provide the bucket hinge pins, at the point of driven engagement with the sprocket teeth, with readily removable bearing sleeves so that such sleeves may be removed and replaced—after normal wear—without replacing such hinge pins. All bushings and hinge pins also, if worn, are easily replaceable.

A further object of the invention is to provide a practical bucket elevator, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of a section of the bucket elevator as engaged with a sprocket.

Fig. 2 is a longitudinal section of one bucket on line 2—2 of Fig. 4.

Fig. 3 is a similar view on line 3—3 of Fig. 4.

Fig. 4 is a cross section on line 4—4 of Fig. 1.

Fig. 5 is a cross section on line 5—5 of Fig. 2.

Fig. 6 is a fragmentary longitudinal section on line 6—6 of Fig. 5.

Fig. 7 is a fragmentary plan view of one of the female ear units of a detached bucket.

Fig. 8 is a fragmentary elevation of the complete bucket elevator, somewhat diagrammatic.

Referring now more particularly to the characters of reference on the drawings, the improved

2.

bucket elevator comprises a plurality of relatively deep buckets 1 hinged together at adjacent ends, as indicated generally at 2, and which hinge assembly is hereinafter described in detail, to form an endless, articulated chain carried at top and bottom by transversely spaced sprockets 3 and 3a, respectively. See Fig. 8. At least one pair of sprockets is driven.

Each bucket 1 includes transversely spaced side plates 4 connected by opposed front and back walls 5 and 6 merging at adjacent ends in a bellied back portion 7 which increases the bucket capacity; the walls 5 and 6 diverging, as shown, and being somewhat diagonal to the path of movement whereby the bucket inclines upwardly toward its open end when traveling in the upwardly moving run of the elevator. See Figs. 1 and 3. If desired, a cutting lip or digging teeth may be applied to the lip of the front and bottom wall 5.

Intermediate the inner and outer edges thereof, each side plate is formed lengthwise thereof, and from end to end, with a laterally outwardly extending offset 8, and a skirt 9 extends inward from the outer edge of such offset whereby to form a radially inwardly opening channel 10. Like channels 10 are thus formed on opposite sides of each of the buckets.

At adjacent ends of the channels 10 adjacent buckets are formed with cooperating male and female ear units, indicated generally at 11 and 12, respectively; such ear units being constructed and hinged together as follows:

Each male ear unit 11 is formed on one end of a corresponding channel 10 and includes a transversely spaced pair of ears 13 which comprise longitudinal extensions of opposite sides of said channel.

Each female ear unit 12 is similarly formed but on the opposite end of the corresponding channel and comprises a pair of ears 14 projecting longitudinally from and beyond the sides of said channel.

The buckets are thus arranged with a male ear unit 11, and a female ear unit 12, on opposite ends of each channel 10; the adjacent male and female ear units of end to end buckets engaging together with the male ears 13 inwardly of the female ears 14 as shown. Laterally inward from each male ear unit 11, adjacent side wall 4 is pocketed as at 15 to permit the adjacent female ear 14 to enter for positioning in engagement with the corresponding male ear 13.

A transversely tubular housing 16 extends between the male ear units 11 in the plane of the

wall 5 of each bucket, and includes bushings 17 whose bore aligns with holes 18 and 19 in the ears 13 and 14 of the cooperating male and female ear units 11 and 12, respectively.

A hinge pin 20 extends through the bushing 17, and through both pairs of cooperating male and female ear units at adjacent ends of the buckets, hinging the latter together. Cross pins 21, retained in seats 22 on the outside female ears 14, prevent rotation and axial displacement of each hinge pin 20.

Removable bearing sleeves 23 are disposed on each hinge pin between, and engaged through, the ears 13 of each male ear unit 11; each such bearing sleeve being affixed at its outer end to a radial locking plate 25 removably secured to the adjacent ear 13 by a cap screw or rivet 26. The outside ears 14 are offset outwardly sufficiently to permit the locking plates 25 to engage between said ears 14 and the adjacent ears 13.

By reason of the described arrangement the bearing sleeves 23 traverse the cooperating ear units adjacent the ends of the channels 10, and, as supported by the pins 20, are driven by engagement with the teeth 27 of the sprockets 3 and 3a. Between the bearing sleeves 23 the peripheral portions of the sprockets 3 run in and are shrouded or guarded by said channels 10 to prevent access of foreign substance to said sprockets.

Access of any such foreign substance to the sprocket teeth 27 and to the engaged bearing sleeves 23 from the buckets and through the cooperating hinged ear units 11 and 12 is prevented by lapping arcuate lips 28 and 29 on said units between the ears thereof; such lips being concentric to the corresponding pin 20, and of a length to always remain in such lapped relation.

A projecting stop 30 on one ear 13 of each male ear unit 11 engages in a longitudinal slot 31 in the lip 30 of the adjacent lip 29 of the corresponding female ear unit 12 so as to prevent inwardly buckling of the adjacent buckets of the chain beyond dead center when free of the sprockets.

Spillage from the buckets at the back, and over the edge 32 of the back walls 6 cannot occur because said edge terminates close to the tubular housing 16 and traverses a concentric path upon relative hinging between buckets. See Fig. 6.

It will thus be seen that the hinge assemblies of adjacent buckets, and the working portions of the sprockets 3, are effectively shielded against access of material from the buckets.

For stiffening and protecting the buckets, flanges 33 extend from the end walls 5 at opposite ends thereof; said flanges actually being continuations of the side plates 4.

Further strengthening is accomplished, when the bucket is wide, by a central longitudinal partition 34 in each bucket, which partition includes an ear 35 at one end which enters a pocket 36 in the adjacent bucket and intersects the tubular housing 16 and bushing 17 thereof for support on the cross pin 20 intermediate its ends.

When normal wear requires, the bearing sleeves 26 are easily removed and replaced, after removal of pins 20 and separation of the buckets, by detaching the plates 25 and sliding said sleeves free of the ears 13.

The hinge pins and bushings 17 are likewise replaceable; said bushings being preferably slotted and engaged by a projection of wall 7 entering

the bushing bore, as shown in Fig. 3. This prevents undesired rotation of the bushings.

From the foregoing description it will be readily seen that there has been produced such a device as substantially fulfills the objects of the invention as set forth herein.

While this specification sets forth in detail the present and preferred construction of the device, still in practice such deviations from such detail 10 may be resorted to as do not form a departure from the spirit of the invention, as defined by the appended claims.

Having thus described the invention, the following is claimed as new and useful and upon 15 which Letters Patent is desired:

1. A bucket elevator comprising a plurality of buckets, the end plates of each bucket being offset intermediate their inner and outer edges, a skirt projecting from along the outer edge of each of the offsets whereby to form channels between the skirts and the sides of the bucket, a pair of spaced apart ears adjacent one end of each channel, and another pair of spaced apart ears adjacent the other end of each channel, the ears on one end of the channel on one bucket 20 matchingly engaging the ears on the opposite end of the channel on an adjacent bucket, said matching ears having co-axial bores, the spacing between the ears forming a continuation of the 25 channels from bucket to bucket, and a bearing pin journaled in the bores and projecting transversely across the channels.

2. A structure as in claim 1 including bearing sleeves about the pin, such sleeves being removably supported between the matchingly engaged 30 ears.

3. A structure as in claim 2 in which the supporting means for the sleeves comprises a locking plate on one end of the sleeve, said plate 40 being detachably fixed to one of the ears.

4. A structure as in claim 1, including a tubular housing formed in one wall of the bucket co-axially with the bores in the ears, the bearing pin being journaled within said housing.

45 5. A structure as in claim 1 including an arcuate lip at the end of each channel, the curve of the lips being concentric with the axis of the pin, the lips at the ends of the channels in one bucket continuously overlapping the lips at the 50 ends of the channels in adjacent buckets.

6. A structure as in claim 1 in which the buckets each consist of transversely spaced side plates and opposed front and back walls merging together at their rear edges, a tubular housing 55 formed in the front wall co-axially with the bores in the ears and having its outer surface projecting beyond the faces of the wall, the pin being journaled in the housing, the outer edge of the back wall of one bucket terminating immediately adjacent the outer surface of the housing on the adjacent bucket and swinging concentrically of the same with relative hinging movement between the buckets.
